(57) **CLAIM**

The ornamental design for a case for mobile telephone, as shown and described.

DESCRIPTION

FIG. 1 is a front, right-side, and top perspective view of a case for mobile telephone showing my new design;

FIG. 2 is a rear, left-side, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right-side, and top perspective view thereof showing the support stand portion of the case in an extended position.

The broken lines in the drawings depict portions of the case for mobile telephone that form no part of the claimed design.
